UNITED STATES PATENT OFFICE.

PAUL BALTHASAR WEIS, OF AURORA, ILLINOIS, ASSIGNOR TO AURORA DOOR HANGER AND SPECIALTY COMPANY, OF AURORA, ILLINOIS, A CORPORATION OF ILLINOIS.

FOLDING-DOOR HANGER EQUIPMENT.

1,349,399.

Specification of Letters Patent. Patented Aug. 10, 1920.

Application filed August 15, 1919. Serial No. 317,662.

To all whom it may concern:

Be it known that I, PAUL B. WEIS, a citizen of the United States, and a resident of Aurora, in the county of Kane and State of Illinois, have invented certain new and useful Improvements in Folding-Door Hanger Equipments, of which the following is a full, clear, and exact specification.

My invention is concerned with folding door supports of the type in which a track is employed for the door, upon which runs a hanger secured to an inner leaf of the door so that as it is opened and folded, the hanger moves from the inner to the outer end of the track, thus permitting the door to open and relieving the racking strain on the hinges. Prior to my invention, so far as I am aware, these supports were of two types.

In the older type, the track was directly above and parallel to the doors when they were closed, but this location of the tracks had the objection that although the doors could be opened and folded, they could not be swung out of the doorway, and this necessitated employing an unnecessarily wide doorway to get the desired effective width.

In a later type developed to overcome this objection, the tracks were placed outside of the doorway and at an angle to the doors in their closed position so that they could be opened, folded and swung entirely outside of the doorway. This type is open to the very serious objection that the position of the outer end of the tracks has to be carefully adjusted for different thicknesses of doors, or the number of the leaves of the door, or for varying positions to which the folded and open doors are finally swung.

By my invention, I obviate the difficulties of both of these old types by placing the hanger track outside of the doorway and parallel to the door, and employing a transverse track upon which the outer end of the hanger track moves when the door is opened and folded so that no adjustment whatever is required as the outer end of the hanger track automatically moves out on the transverse track when the door is opened and folded just as far as may be necessary and without having to take into consideration

either the thickness of the door, the number of leaves, or the position to which the folded and open door is finally swung.

To illustrate my invention, I annex hereto two sheets of drawings in which the same reference characters are used to designate identical parts for all the figures of which—

Fig. 1 is an elevation of a pair of folding doors mounted upon my novel supports, showing the doors in their closed position;

Fig. 2 is a top plan view in section on the line 2—2 of Fig. 1, showing the doors and tracks in their closed position in full lines and in their open position in dotted lines;

Fig. 3 is a detail of the inner end of the support on an enlarged scale, seen in section on the line 3—3 of Fig. 1;

Fig. 4 is a detail of the same mechanism as seen from the left-hand side of Fig. 3;

Fig. 5 is a detail showing the transverse track as seen in section on the line 5—5 of Fig. 1, but on an enlarged scale;

Fig. 6 is a top plan view of the same;

Fig. 7 is a detail as seen in section on the line 7—7 of Fig. 5;

Fig. 8 is a view of the mechanism shown in Fig. 7 as seen from the left-hand side; and

Fig. 9 is a detail in section on an enlarged scale on the line 9—9 of Fig. 5.

In the drawings, I have indicated the customary side walls 10 and ceiling 11 of a room diagrammatically, together with the end wall 12 having the doorway 13 in which are mounted a pair of folding doors made up of the inner leaves 14 mounted by the hinges 15 on the outer leaves 16 which in turn are supported by the hinges 17 secured to the sides of the doorway in the customary manner.

Near the inner edges of the inner leaves 14 are the brackets 18 secured by the bolts 19 and having the hangers 20 adjustably mounted thereon in the customary manner so that the wheels 21 of the hanger may center accurately on the track flanges 22 of the customary track 23, which is pivotally supported at its inner end by the yoke 24 in which it is secured which is pivoted by the bolt 25 to the supporting bracket 26 secured to the end wall 12 above the doorway 13.

100

The outer ends of the tracks 23 have secured thereon the sockets 27, which are provided with the outwardly projecting axle 28 for the grooved roller 29 mounted thereon to 5 coöperate with the transverse track 31, which may be conveniently made of a bar of iron having the lug 32 formed on its rear end and extending into the aperture 33 formed in the horizontally outwardly projecting flange 34 of the bracket 35 secured to the wall 12 in any suitable manner as by the screws 36. This bracket is conveniently made of a piece of strap iron and has its upper end 37 offset as seen, and provided 10 with an aperture 38 through which passes the brace rod 39, the lower threaded end of which passes through the aperture 40 in the upward and outwardly turned end 41 of the track 31, and has the nut 42 and the lock nut 43 secured thereon. With the construction 15 shown, the track 31 is free to swing on the lug 32 as a pivot through several degrees so that it can accommodate itself to the varying angular positions of the track 23. This 20 swinging transverse track enables me to use the same track and fittings on both sides of the door.

The operation of my improved support will be readily apparent. When the doors 30 are closed, the tracks 23 are in the full line position shown parallel to the closed doors, and as the doors are opened and folded the hangers 20 run out in the tracks 23, which swing out to the dotted line position shown 35 in Fig. 2, and which position will be just as far as is necessary to accommodate the open and folded doors, irrespective of their thickness, the number of leaves or the position to which they are moved. To illustrate this 40 the door on the right-hand side of Fig. 2 is shown as opened less than the door on the left-hand side with the result that the co-operating track 23 is not swung out so far as the track 23 on the other side. When the 45 doors are closed, the tracks swing back to their normal parallel position, and it will be obvious that in equipping folding doors with these supports, it is not necessary to supply various sizes of the transverse tracks 50 or to make any adjustment therein, or to supply different tracks for the two sides of the doorway, as all that is necessary is to mount the tracks in position to receive the rollers 29 when the inner ends are properly 55 adjusted. To prevent the accidental disengagement of the roller 29 from the track 31, I form the end of the socket 27 of a Z-shaped piece with the lower horizontal flange 30 extending beneath the track 31, and to prevent 60 the possible disengagement of the track 31 from the supporting bracket 35, I pass the cotter pin 44 through a suitable aperture in the bottom of the lug 32.

While I have shown and described my in-

vention as embodied in the form which I at present consider best adapted to carry out its purpose, it will be understood it is capable of modifications, and that I do not desire to be limited in the interpretation of the following claims, except as may be necessitated by the state of the prior art. 70

What I claim as new and desire to secure by Letters Patent of the United States is:

1. In an apparatus of the class described, the combination with a hanger secured to 75 a folding door, of a horizontal track therefor pivotally supported at its inner end by the door frame and standing parallel to the closed door, and means for supporting the outer end of said track, upon which means it rolls and permitting it to swing away from the doorway as the door is folded and opened without any increased resistance resulting from said swinging movement.

2. In an apparatus of the class described, 80 the combination of a hanger secured to a folding door, of a horizontal track therefor pivotally supported at its inner end by the door frame and standing parallel to the closed door, and a transverse track upon 90 which the outer end of the horizontal track rolls outward without any increased resistance as the door is folded and opened.

3. In an apparatus of the class described, the combination with a hanger secured to 95 a folding door, of a horizontal track therefor pivotally supported at its inner end by the door frame, and a swinging support for the outer end of the track permitting it to swing without resistance away from the 100 doorway as the door is folded and opened.

4. In an apparatus of the class described, the combination with a hanger secured to a folding door, of a horizontal track therefor pivotally supported at its inner end by the door frame, an antifriction roller mounted upon the outer end of said track, and a transverse track upon which the roller runs as 105 the horizontal track swings outward when the door is folded and opened, pivotally supported to swing on the vertical axis near the door.

5. In an apparatus of the class described, the combination with a hanger secured to a folding door, of a horizontal track therefor pivotally supported at its inner end by the door frame, an antifriction roller mounted upon the outer end of said track, a bracket secured to the door frame, and a horizontal track upon which the roller runs 115 120 pivoted at its ends on a vertical axis to said bracket.

6. In an apparatus of the class described, the combination with a hanger secured to a folding door, of a horizontal track therefor pivotally supported at its inner end by the door frame, an antifriction roller mounted upon the outer end of said track, a bracket 125

secured to the door frame, a horizontal track upon which the roller runs pivoted at its ends on a vertical axis to said bracket, and a brace rod loosely connected at its upper end 5 to the top of the bracket and at its lower end to the outer end of the transverse track.

In witness whereof I have hereunto set my

hand and affixed my seal this 12th day of Aug., A. D. 1919.

PAUL BALTHASAR WEIS. [L. S.]

Witnesses:

JOHN K. NEWHALL,
C. W. HARKNESS.
